UNITED STATES PATENT OFFICE.

JOSEPH J. COSGROVE, OF PHILADELPHIA, PENNSYLVANIA, ASSIGNOR TO STANDARD SANITARY MANUFACTURING COMPANY, OF PITTSBURG, PENNSYLVANIA, A CORPORATION OF NEW JERSEY.

WATER-CLOSET AND SOIL-PIPE CONNECTION THEREFOR.

No. 919,283.

Specification of Letters Patent.

Patented April 20, 1909.

Application filed October 18, 1908. Serial No. 488,636.

To all whom it may concern:

Be it known that I, JOSEPH J. COSGROVE, a citizen of the United States, residing at Philadelphia, in the county of Philadelphia 5 and State of Pennsylvania, have invented certain new and useful Improvements in Water-Closets and Soil-Pipe Connections Therefor, of which the following is a specification.

This invention has relation to water closets and soil pipe connections therefor and has for its object the provision of a novel all-metallic connection between the outlet passage of the bowl of a water closet 15 and the soil pipe leading therefrom.

It has been customary heretofore to interpose between the outlet passage portion of a water closet and the soil pipe some form of cement or elastic packing, but connections so made are objectionable, owing 20 to the difficulty of making and maintaining an air tight and water tight joint. In Letters Patent of the United States Nos. 870,017-870,018—and 870,085, dated November 5th., 1907, I have shown and described several forms of water closet connections in which the connection between the water closet bowl and the soil pipe is of the ball and socket type, the soil pipe in each case 25 being provided with a bell or socket having a spherical seat to receive a spherical spigot or thimble projecting below the end of the outlet passage of the bowl.

In carrying my present invention into effect I employ, in connection with a water closet bowl having a spherical spigot or thimble projecting below the outlet passage, such as are shown and described in the before mentioned Letters Patent; a soil pipe having 30 a bell or socket to receive the said spigot or thimble but, instead of forming the seat directly in the walls of the bell or socket, I form the seat portion in a separate piece from the bell or socket proper, the two parts, 35 that is the seat portion and the bell or socket proper being screwed one into the other so as to provide a tight, secure connection between these parts which will permit of the seat portion being vertically 40 adjusted in the manner and for the purposes hereinafter described.

Referring to the accompanying drawing in which I have illustrated my present invention applied to various types of all

metallic and earthenware water closets and 55 soil pipe connections, Figure 1 is a fragmentary vertical sectional view of a portion of a water closet bowl and a portion of a soil pipe with my proposed connection, the spigot end of the outlet passage of the bowl 60 being formed integral with the bowl. Fig. 2 is a view similar to Fig. 1 with the spigot end of the outlet passage of the bowl formed separate therefrom and screwing therein. Fig. 3 is a view similar to Figs. 1 and 2 but 65 having the outlet passage terminating in a spherical seat and having a thimble with a spherical peripheral surface interposed between the outlet passage of the bowl and the soil pipe.

The bowl or closet which is designated 1 is of the usual or any desired type and is provided with a laterally extending base 2, having the depending flange 3, at its edge, this flange resting on the floor 4, so as to 70 leave a space 5, between the base and the floor. The base 2 is pierced for the passage of bolts 6 upon which are screwed nuts 7, that serve to connect the base with a flange 8 carried by the bell or socket 9 of a soil pipe 80 10, said bell or socket being connected to the soil pipe by a screw coupling 11 or in any other suitable manner.

The outlet passage of the bowl 1 is designated 12 and in the form shown in Fig. 1 an 85 integral spigot 13 is provided at the extremity of the outlet passage, this spigot having a spherical peripheral surface 14.

In the form shown in Fig. 2 of the drawings a spigot 13' is provided this spigot being 90 in a separate piece from the closet bowl and screwing thereinto and being provided with a spherical peripheral surface 14', while in the form shown in Fig. 3 the outlet passage of the bowl is formed with a smooth spherical socket in which is seated a thimble 13" 95 having a spherical peripheral surface 14" coinciding with the spherical surface of the socket in the outlet passage of the bowl.

Each of the several forms of water closet 100 bowl above described may be used in connection with my present improvement which I will now describe in detail.

The bell or socket 9 is interiorly screw threaded at 15, and receives a shelf 16, 105 which is exteriorly screw threaded at 17 and is formed with a spherical internal surface 18 that serves to receive and act as an

air and water tight seat for the spherical spigot or thimble respectively of the several bowls shown in Figs. 1, 2 and 3.

The spherical seating surface 18 of the shell 16 acts in conjunction with the peripheral spherical surface of the spigot or thimble to form a ball and socket joint connection and therefore the bowl can, if necessary, be set in position with the longitudinal axis of the outlet passage at an angle to the longitudinal axis of the drain pipe without detriment to the connection. The shell 16 being connected to the bell or socket 9 by a screw connection, the shell is vertically adjustable in the bell or socket and this adjustability constitutes a valuable feature of my improvement as it insures a perfect joint being easily made notwithstanding any irregularity of the floor or of the flanges 20 3 or 2.

In addition to the adjustability of the flange, the shell 16 can be removed and a plug screwed in to close the opening while the drainage system is being tested. Further it permits the entire drainage system to be complete up to this point, ready for the closet to be set after the system is tested and the floors and walls of the toilet rooms finished.

I claim:

1. The combination with a water closet having an outlet passage and having a horizontally extending base with a depending flange adapted to rest on the floor and a soil pipe, of a spigot extending from said outlet passage and having an externally spherical end, a bell or socket carried by the soil pipe said bell having a flange adapted to rest on the floor within the depending flange of the base of the closet and a separate seat arranged in said bell or socket and having a spherical seating surface which receives the spherical end of the spigot.

2. The combination with a water closet having an outlet passage and a horizontally extending base with a depending flange adapted to rest on the floor and a soil pipe, of a spigot extending from said outlet passage and having an externally spherical end, a bell or socket carried by the soil pipe said bell having a flange adapted to rest on the floor within the depending flange of the closet base and a shell screwing into said bell or socket and having a spherical seating surface which receives the spherical end of the spigot.

3. The combination with a water closet

having an outlet passage and a horizontally extending base with a depending flange adapted to rest on the floor and a soil pipe, of a spigot extending from said outlet passage and having an externally spherical end, a bell or socket carried by the soil pipe said bell having a flange adapted to rest on the floor within the depending flange of the closet base and a vertically adjustable seat portion arranged in said bell or socket and having a spherical seating surface which receives the spherical end of the spigot.

4. The combination with a water closet having a depending connection member with a spherical peripheral surface and having a horizontally extending base with a depending flange, of a soil pipe, a bell or socket carried by the soil pipe and having a flange adapted to lie within the depending flange of the base, with the lower surfaces of both said flanges in the same plane and a seat portion arranged in the bell or socket and having a spherical seat.

5. A bell or socket for soil pipes having a horizontally extending floor flange and a vertically adjustable seat portion.

6. A bell or socket for soil pipes having a horizontally extending floor flange and having a vertically adjustable seat portion with a spherical seating surface.

7. The combination with a water closet having an outlet passage and having a horizontally extending base and a spigot extending from said outlet passage and below the said base, and means for supporting said base above the floor, of a soil pipe, a bell or socket connected to the soil pipe and having a horizontal flange adapted to rest between the base of the closet and the floor and an adjustable seat portion arranged in the bell or socket and having a seat to receive said spigot.

8. A bell or socket adapted to be connected to a soil pipe, said bell having a flange extending outwardly from its lip, and a flange extending inwardly from its lip, said last named flange being internally screw threaded, in combination with an externally threaded shell screwing into said screw threaded flange and formed with a spherical seating surface.

In testimony whereof I have affixed my signature, in presence of two witnesses.

JOSEPH J. COOGROVE.
